UNITED STATES PATENT OFFICE.

DIEDRICH WILHELM ERNSTING, OF BREMEN, GERMANY.

DEVICE FOR CLAMPING CORDS, &c.

SPECIFICATION forming part of Letters Patent No. 291,172, dated January 1, 1884.
Application filed October 24, 1883. (No model.)

To all whom it may concern:

Be it known that I, DIEDRICH WILHELM ERNSTING, of Bremen, in the Empire of Germany, have invented a new and useful Improvement in Devices for Clamping Cords or Ropes, of which the following is a specification.

This invention has reference to an improved device for reliably clamping cords, ropes, or chains; and the invention consists of a device for clamping cords or ropes, composed of a supporting main plate, of a U-shaped clasp-plate pivoted to ears of the supporting-plate, and of a second U-shaped clasp-plate that is pivoted to the first clasp-plate with its open side inward, so that the lower edges or jaws of the clasp-plates "bite" the cord or rope that is passed through between the two clasp-plates, as will appear more fully hereinafter, and finally be pointed out in the claims.

In the accompanying drawings, Figure 1 represents a front view of my improved clamping device for cords and ropes; and Figs. 2 and 3 are vertical transverse sections, showing the same respectively as released from and applied to the cord or rope.

Similar letters of reference indicate corresponding parts.

A in the drawings represents the supporting main plate of my improved clamping device, which plate is made of U-shaped cross-section and screwed at the upper and lower ends to a window-easing when used for clamping cords of window shades or to any other suitable point of support when used for clamping hoisting ropes or chains.

To the supporting-plate A is pivoted, at D, a clasp-plate, B, which is also of U-shaped cross-section, while a second clasp-plate, C, of similar cross-section, is also connected to the first clasp-plate, B, by a second pivot, E. The clasp-plate C is so connected to the clasp-plate B that its open inner part faces the open part of the clasp-plate B, while its closed middle part is on the outside, as shown in Fig. 2. The cord, rope, or chain T to be clamped is passed through the space formed between the pivots D and E and the clasp-plate C, and can be moved freely up and down between the clasp-plates B and C when they are stored away in vertical positions on the main plate A, as shown in Fig. 2. As soon as the lower end of the cord or rope T is moved sidewise in the direction of the arrow shown

in Fig. 2, the clasp-plate B is turned outwardly on its pivot-pin D, and thereby the cord or rope T placed between the lower edges, f and g, of the clasp-plates B and C, as shown in dotted lines in Fig. 2. On releasing the cord or rope the clasp-plates B and C are drawn in upward direction by the action of the weight of the shade roller or weight, and thereby the edges of the clasp-plates B and C, which edges act like jaws and bite into the cord or rope, so that the same is rigidly held in this position, as shown in Fig. 3. The greater the tension that is exerted on the cord or rope the greater will be the biting action exerted thereon by the clamping-edges f and g. By pulling the cord or rope downward the clasp-plates drop back into their vertical positions into the main plate A, whereby the cord or rope is released and its free play secured again.

The clamping device can be made cheaply of sheet metal of suitable size and strength, and is readily operated, simply moving the cord or rope sidewise and then letting it go, by which motions the reliable clamping action of the clasp-plates on the cord or rope is secured.

Having thus described my invention, I claim as new and desire to secure by Letters Patent—

1. A device for clamping cords, ropes, or chains, consisting of a flanged main plate, A, a U-shaped clasp-plate, B, pivoted to the main plate, and of a second U-shaped clasp-plate pivoted with its open side toward the clasp-plate B, substantially as set forth.

2. The combination of a supporting main plate, A, a U-shaped clasp-plate, B, pivoted to the main plate, a second U-shaped clasp, C, pivoted with its open side toward the clasp-plate to the same, and a cord, rope, or chain, T, that is passed through the space between the pivots of the clasp-plates and the closed middle portion of the clasp-plate C, and adapted to be clamped by the lower edges or jaws of the clasp-plates, substantially as specified.

In testimony whereof I have signed this specification in the presence of two subscribing witnesses.

DIEDRICH WILHELM ERNSTING.
